UNITED STATES PATENT OFFICE

105,036

DESIGN FOR A TABLECLOTH OR SIMILAR ARTICLE

Francis Tausend, New York, N. Y.

Application May 17, 1937, Serial No. 69,390

Term of patent 3½ years

To all whom it may concern:

Be it known that I, Francis Tausend, a citizen of the United States, residing at New York, in the city, county, and State of New York, have invented a new, original, and ornamental Design for a Tablecloth or Similar Article, of which the following is a specification, reference being had to the accompanying drawing, forming part thereof, wherein—

The figure is a plan view of one-quarter of a tablecloth or similar article showing my new design. The quarter section of the table cloth is indicated by the dot and dash line in the drawing, the other three sections being identical, but arranged in proper relation to complete the cloth.

I claim:

The ornamental design for a tablecloth or similar article substantially as shown and described.

FRANCIS TAUSEND.
